Inventor

Arthur H. Wettwer

By *Waco C. Huddles*

Attorney

UNITED STATES PATENT OFFICE.

ARTHUR H. WETTWER, OF RICE LAKE, WISCONSIN.

WRENCH.

Application filed December 12, 1921. Serial No. 521,821.

To all whom it may concern:

Be it known that I, ARTHUR H. WETTWER, a citizen of the United States, residing at Rice Lake, in the county of Barron, State of Wisconsin, have invented certain new and useful Improvements in Wrenches; and I do hereby declare the following to be a full, clear, and exact description of the invention, such as will enable others skilled in the art 10 to which it appertains to make and use the same.

This invention relates to new and useful improvements in wrenches.

One object of the invention is to provide 15 a wrench which is formed from the minimum number of parts, which parts are simple in construction and cheap to manufacture.

Another object of the invention is to provide 20 a wrench wherein the lever which holds the movable jaw in adjusted position is so arranged that it is adapted to be gripped with the shank of the wrench, thereby securing against displacement of the movable jaw, 25 while engaged with the work.

Other objects and advantages will be apparent from the following description when taken in connection with the accompanying drawing.

30 In the drawing—

Figure 1 is a side elevation of a wrench made in accordance with the invention.

Figure 2 is an edge view of the wrench looking toward the open side of the groove.

35 Figure 3 is a vertical longitudinal sectional view taken centrally through the wrench on the line 3—3 of Figure 2.

Referring to the accompanying drawing 10 represents a handle shank which has an 40 enlarged head 11 formed on its upper end. Formed at one end of the upper face of the head 11 is the stationary jaw 12, and longitudinally in said upper face is an inverted T-shaped groove or channel 13, the same extending through the opposite ends of the 45 head and beneath the stationary jaw 12. Slidable in this channel 13 is the inner bar 14 of the movable jaw 15, the outer end of said bar being formed with a transverse

notch 16 for the reception of the transverse 50 pin 17 disposed in the outer end of the channel 13. This pin limits the outward sliding movement of the movable jaw 15, as will be understood. On the lower face of the bar 14 there are formed the series of teeth 18. 55

Formed longitudinally in one edge of the handle shank 10, and extending from the end of the channel 13 which lies beneath the stationary jaw 12, to a point adjacent the other end of the shank, is a groove 19, and pivotedly mounted within this groove, directly beneath the stationary jaw 12, is a lever 20, the pivotal end of which is formed with a series of teeth 21 adapted to engage with the teeth 18 when the lever is swung 60 into the groove 19. A portion of the pivotal end of the lever 20 remains without the upper end of the shank 10 and in the opposite faces of this portion of the lever there are formed finger receiving notches 22, within 65 which the fingers of the operator are to be placed to swing the lever in and out of the groove 19. 70

When the lever 20 is disposed within the groove 19, and the movable jaw 15 has been 75 properly adjusted to cooperate with the jaw 12, to grip the work, the operator's hand will grasp the shank 10 together with the lever 20, thus firmly holding the lever within the groove, and maintaining the teeth of 80 the lever in proper engagement with the teeth of the jaw 15. To adjust the jaw it is only necessary to swing the lever 20 out of the groove 19, then slide the jaw 15, to the proper position along the the groove or channel 13, after which the lever 20 is again 85 swung into the groove 19, to engage its teeth with those of the jaw 15.

The outer free end of the lever 20 is formed with a screw-driver point 20'. 90

What is claimed is:

A wrench comprising a shank having a head on one end formed with a stationary jaw, said shank having a longitudinal groove formed in one of the narrow faces 95 thereof, said groove being enlarged at one end and entering the stationary jaw, a channel formed longitudinally in the outer face

of the head, said channel intercepting the enlarged end of the groove at an angle thereto, a movable jaw slidable in said channel, and a tapered lever movably supported in the groove of the shank, the lower face of the lever snugly fitting the bottom of the groove, the upper face of the lever being slightly above the edges of the groove to be

gripped with the shank to engage the lever with the movable jaw.

In testimony whereof, I have affixed my signature, in the presence of two witnesses.

ARTHUR H. WETTWER.
